(57) **CLAIM**

We claim the ornamental design for a male enhancement and testicle retraction prevention device, as shown and described.

DESCRIPTION

FIG. 1 is a perspective view of a male enhancement and testicle retraction prevention device, showing our new design;

FIG. 2 is an exploded perspective view thereof;

FIG. 3 is a front elevational view thereof;

FIG. 4 is a rear elevational view thereof;

FIG. 5 is a left-side elevational view thereof, the right-side elevational view being a mirror image thereof;

FIG. 6 is a top plan view thereof;

FIG. 7 is a bottom plan view thereof; and,

FIG. 8 is a cross-sectional view thereof, taken generally along lines 8-8 of FIG. 5.

The broken lines showing male genitalia in FIG. 1 depict environmental matter and form no part of the claimed design.
